UNITED STATES PATENT OFFICE.

GEORGE W. TROUTMAN, OF CALDWELL, KANSAS.

TRAVERSING JACK.

1,131,018.

Specification of Letters Patent.

Patented Mar. 9, 1915.

Application filed June 25, 1914. Serial No. 847,192.

To all whom it may concern:

Be it known that I, GEORGE W. TROUTMAN, a citizen of the United States, residing at Caldwell, in the county of Sumner and State of Kansas, have invented a new and useful Traversing Jack, of which the following is a specification.

My invention relates to a traversing jack which is particularly adapted to assist in the accurate lining up of crank shafts, journals and shafting in general.

One of the leading objects of my invention is to provide a simple, compact, light weight traversing jack to assist in the accurate lining up of shafting in the bearing boxes in which the bearings composed of Babbitt or other anti-friction metals are cast.

It is well known that in lining up the crank shafts on engines and the journals and shafting on many types of machinery that the bearing boxes are located on or so close to the main frame or body of the machine in which they operate that it is very difficult to get any suitable means to assist in getting the shafting accurately lined up in the boxes preparatory to casting the bearings and my traversing jack being very compact, readily adapts it to being used where there is but little space and where an ordinary jack could not be used. The device is also adapted to many uses in general machine and repair work where it is necessary to move objects both vertically and horizontally.

Another object is to provide the device with the necessary mechanism to give it both a vertical and horizontal movement so as to adapt it to moving the object it is desired to move, either upward or downward or laterally, whichever is desired.

A further object is to provide the device with a rectangular shaped base member having sides and ends forming a rectangular shaped recess open at the top.

Another object is to provide the device with a traversing member adapted to move upon the upper faces of the base member and sustain the weight of the load placed upon the device.

A further object is to provide the device with a plurality of vertically positioned guide and guide-way members which are adapted to accurately guide the upper member and its mechanism in its vertical movement.

Another object is to provide the device with a rectangular-shaped upper member that is adapted to having a vertical movement imparted to it and that will move with the traversing member and that has a centrally located flattened V-shaped depression or its equivalent in its upper surface adapted to retain thereon a shaft or other object which it is desired to move.

A further object is to so design the device that it will occupy but little space and so that all its working parts can be machined to an accurate fit without excessive expense.

By means of the device hereinafter particularly described, any crank shaft, journal or shaft can be quickly and accurately lined up and any object to which the device is adapted to moving can be quickly moved both vertically and horizontally and put in the desired position.

To the above end, the invention consists in the novel construction, combination, and arrangement of parts, as hereinafter more fully described, illustrated and claimed.

In the accompanying drawings, Figure 1 is a combined side elevation and top plan view of a traversing jack embodying the present invention: Fig. 2 is a vertical cross section through Fig. 1 on the line A A, a portion of the cylindrical surfaces being projected; Fig. 3 is a side elevation of the upper member, parts of it being in section, and shows the upper member and the two vertical guide members all formed in one piece and rigid together; Fig. 4 is a perspective view of a portion of the base member and shows the ends of the base member detachable from its sides and base; Fig. 5 shows a pair of the traversing jacks positioned on a horizontal surface and a piece of shafting mounted on the depressions in the upper members; Fig. 6 is a side elevation of the traversing member, parts of it being in section and shows the vertical guide way members and the member in which the screw works, all formed in one piece and rigid together.

The traversing jack contemplated in this invention and which is adapted to the various lines of work previously described comprises a rectangular-shaped base member, composed of the sides 1 or their equivalent, these sides are preferably planed and are formed rigid with the base 2, the upper surfaces 3 of the sides 1 are planed and polished and adapted to permit the travers-

ing member 20, whose lower surface 21 is planed so as to easily slide upon these surfaces; these have a sufficient width to sustain the weight placed upon them by the 5 traversing member 20.

The ends 4 of the base member are preferably rigid and formed with the base and sides of the base member, or they may be composed of a separate member as shown 10 by 4^a in Fig. 4 and be rigidly secured to the sides 1 and the base 2 by means of properly disposed screws or their equivalent. The centrally located rectangular shaped recess 5^a or its equivalent being formed by the 15 sides 1, the base 2, and the ends 4, provides a protected recess for the horizontally positioned screw member 5 to work in. This screw member 5 is externally screw-threaded and passes through the internally 20 screw-threaded perforation 26 in the member 24; this member 24 or its equivalent is rigidly secured to the under side of the traversing member 20 by means of the upper reduced part 25^a which is slightly larger 25 than its perforation 25 in the traversing member 20; the part 25^a is forced into the perforation 25 by pressure and rigidly secured to the traversing member 20, or the part 25^a may be externally screw-threaded 30 and the perforation 25 internally screw-threaded and 25^a screwed into 25 and thereby rigidly secured to the traversing member 20, or the member 24 or its equivalent may be rigidly formed on the traversing member 35 20 as shown in Fig. 6 in which the traversing member 20, the member 24, the vertical guide-way members 10 and the screw guide-way member 14 are preferably a casting and all formed in one piece and then accurately 40 machined.

From the previous description it will be readily understood that when the screw member 5 is rotated, its threads acting in the threaded perforation 26 in the member 45 24, will actuate the traversing member 20 according to the direction in which the screw member 5 is rotated, and thereby move the entire traversing mechanism and the shaft or load upon it in a lateral direction. 50 The screw member 5, has an enlarged part 6, whose internal surface 6^a or its equivalent is turned so as to be parallel with the planed surfaces of the ends 4, these internal surfaces 6^a at opposite ends of the screw member act as end thrust bearings for the 55 screw member 5.

8 is a semicircular projection centrally located upon the upper surfaces of the ends 4 and forms a portion of the bearing perforation 8^b in the ends 4 in which the screw 60 5 rotates; this semi-circular projection 8 may be omitted if desired and the ends formed level with the surfaces 3, as shown by 4^a.

65 At one of the ends of the screw member

5 is located the bearing member 8^a with its enlarged part 9; this member has an external cylindrical shaped surface indicated by 8^a which is adapted to rotate in the bearing perforation 8^b. This bearing member 70 has its part 8^a centrally perforated at 8^c and the perforation screw-threaded to receive the screw member 5 which is screwed into the threaded perforation 8^c until the bearing member 8^a is rigidly connected to 75 the screw member 5. This bearing member 8^a forms a bearing for the screw member 5 to rotate on and when it is desired to take the device apart, the bearing member 8^a can be unscrewed from the screw member 5 80 which permits the removal of the screw member from the base member and the member 24.

The traversing member 20 or its equivalent as shown in Fig. 2 is perforated at 13 85 to receive the two guide-way members 10, which are cylindrically perforated as shown by 11, the guide-way members 10 are preferably slightly larger than the perforations 13 and are forced into them and rigidly secured to the traversing member 20, the screw guide way member 14 is slightly larger than its perforation 19 and is forced into the perforation 19 and rigidly secured to the traversing member 20 or the guide- 90 way members 10 and 14 may have one of their ends externally screw-threaded and the perforations 13 and 19 may be internally screw-threaded and the members 10 and 14 95 screwed into the perforations 13 and 19 and 100 thereby rigidly secured to the traversing member 20; the screw guide-way member 14 is cylindrically perforated and the perforation screw-threaded as shown by 15 and is adapted to having the externally screw- 105 threaded screw member 16 work vertically in it. This screw member 16 has an enlarged portion 17 with a plurality of perforations similar to 18 which afford means by which the screw member can be rotated, 110 its upper portion 17^a works in a suitable perforation in the upper member 22, by means of this screw member 16, the upper member 22 and its guide members 12, which move vertically in the perforations 11 in the 115 guide-way members 10, can be vertically moved either upward or downward as is desired, the guide members 12 being slightly larger than the perforations 12^a are forced into these perforations and thereby rigidly 120 secured to the upper member 22 which is provided with the central V-shaped depression 23 which is adapted to retain a shaft, journal or other object upon its upper surface and to move it with the upper member 125 either horizontally or vertically or this upper member may have its upper surface plane if it is desired, so as to adapt it to objects with a plane surface.

In operation one or two of the traversing 130

jacks may be used, the base member being positioned upon some stable object such as the floor or upon some part of the machine, the journal, shaft or other object to be moved is positioned upon the upper member and preferably in the V-shaped depression 23 in the upper surface of the upper member 22, if it is desired to raise or lower the shaft or other object, the vertical screw member 16 is rotated either upward or downward until the object is in the desired position; if it is desired to move the shaft or other object laterally, the screw member 5 in the base member is rotated in the proper direction, which moves the traversing member 20 and the upper member 22. From this description it will be readily seen that any shaft, journal or other object it is desired to move either horizontally or vertically or both, can be quickly and easily located in a given position.

While I have shown and described the preferred form of this invention, I desire to have it understood that many changes may be made in the form, construction and arrangement of the parts, without departing from the spirit of my invention.

What I claim is:

1. In a device of the character described, a traversing jack, comprising a rectangular shaped base member whose sides and ends form a central rectangular shaped recess open at the top, said rectangular shaped recess adapted to receive a horizontal screw member, a screw member centrally positioned within said recess, bearing perforations in the ends of said base member adapted to form bearings for the screw member, and means for rotating the screw member, a rectangular shaped traversing member whose lower surface is adapted to slide upon the upper surfaces of said base member, said traversing member having a downward projecting member adapted to traverse in the rectangular shaped recess formed in the previously mentioned base member, a screw threaded perforation in said downward projecting member adapted to receive a horizontally positioned screw member and two vertically positioned, centrally and vertically perforated guide-way members rigidly secured to and projecting upward from the upper surface of said traversing member.

2. In a traversing jack, comprising in combination a rectangular shaped base member having sides and ends forming a rectangular shaped recess open at the top, a horizontal screw member positioned in said recess, bearing perforations in the ends of said base member adapted to form bearings for the screw member and means for rotating the screw member, a rectangular shaped traversing member whose lower surface is adapted to slide upon the upper surfaces of said base member, said traversing member

having a downward projecting member adapted to traverse in the rectangular shaped recess formed in the previously mentioned base member, a screw threaded perforation in said downward projecting member adapted to receive a horizontally positioned screw member, two vertically positioned, centrally and vertically perforated guide-way members rigidly secured to and projecting upward from the upper surface of said traversing member, and a centrally, vertically perforated, screw threaded, vertically positioned screw guide-way member adapted to receive a vertically positioned screw member, said screw guide-way member centrally positioned and rigidly secured to the upper surface of said traversing member.

3. In a combination of the character described, a traversing jack, comprising a base member rectangular shaped, whose sides and ends form a central rectangular shaped recess open at the top, said rectangular shaped recess adapted to receive a horizontal screw member, a screw member centrally positioned within said recess, bearing perforations in the ends of said base member adapted to form bearings for the screw member and means for rotating the screw member, a rectangular shaped traversing member whose lower surface is adapted to slide upon the upper surfaces of said base member, said traversing member having a downward projecting member adapted to traverse in the rectangular shaped recess formed in the previously mentioned base member, a screw threaded perforation in said downward projecting member adapted to receive a horizontally positioned screw member, two vertically positioned, centrally and vertically perforated guide-way members rigidly secured to and projecting upward from the upper surface of said traversing member, and a centrally, vertically perforated, screw threaded, vertically positioned screw guide-way member adapted to receive a vertically positioned screw member, said screw guide-way member centrally positioned and rigidly secured to the upper surface of said traversing member.

4. In a device of the character described, a traversing jack, comprising a rectangular shaped base member having sides and ends forming a central rectangular shaped recess open at the top, adapted to receive a horizontally positioned screw member, a screw member centrally positioned within said recess, bearing surfaces at opposite ends of the screw member, bearing perforations in the ends of said base member adapted to form bearings for the screw member and means

- for rotating the screw member, a rectangular shaped traversing member having its lower surface adapted to slide upon the upper surfaces of the base member, perforated screw threaded means on the lower surface of the traversing member, adapted to receive a screw, a screw member adapted to actuate the traversing member and means for rotating the screw member, a plurality of vertically positioned cylindrically perforated guide-way members rigidly secured to the upper surface of the traversing member and positioned at its opposite ends adapted to receive and guide a plurality of vertically positioned cylindrical shaped guide members, a vertically positioned and centrally located screw-threaded guide-way member rigidly secured to the upper surface of said traversing member and adapted to receive a vertical actuating screw member, a vertically positioned screw member adapted to being actuated within the screw-threaded guide-way member and means for rotating the screw member.
5. In a device of the character described, a traversing jack, comprising a rectangular shaped base member having sides and ends forming a central rectangular shaped recess open at the top, adapted to receive a horizontally positioned screw member, a screw member centrally positioned within said recess, bearing surfaces at opposite ends of the screw member, bearing perforations in the ends of said base member adapted to form bearings for the screw member and means for rotating the screw member, a rectangular shaped traversing member having its lower surface adapted to slide upon the upper surfaces of the base member, perforated screw threaded means on the lower surface of the traversing member, adapted to receive a screw, a screw member adapted to actuate the traversing member and means for rotating the screw member, a plurality of vertically positioned cylindrically perforated guide-way members rigidly secured to the upper surface of the traversing member and positioned at its opposite ends adapted to receive and guide a plurality of vertically positioned cylindrical shaped guide members, a vertically positioned and centrally located screw-threaded guide-way member rigidly secured to the upper surface of the traversing member and adapted to receive a vertical actuating screw member, a vertically positioned screw member adapted to being actuated in the screw-threaded vertical guide-way member, means for rotating the screw member and a rectangular shaped upper member adapted to move with the previously mentioned traversing member, said upper member having a V-shaped depression in its upper surface, and a plurality of vertically positioned guide members rigidly secured to the lower surface of the upper member and adapted to move vertically in the perforations in the guide way members rigidly secured to the traversing member and the previously mentioned vertical screw member adapted to vertically actuate the upper member.
6. In a traversing jack, the combination comprising a rectangular shaped base member having sides and ends forming a central, rectangular shaped recess open at the top, a horizontal screw member centrally positioned in the recess, bearing surfaces at opposite ends of the screw member, bearing perforations in the ends of the base member adapted to form bearings for the screw member, a rectangular shaped traversing member having its lower surface adapted to slide upon the upper surfaces of the base member, perforated screw-threaded means rigidly secured to the lower surface of the traversing member adapted to receive the horizontally positioned screw member and actuate the traversing member when said screw member is rotated, means for rotating the screw member and a plurality of vertically positioned, cylindrically perforated, guide-way members rigidly secured to the upper surface of the traversing member and positioned at its opposite ends adapted to receive and guide a plurality of vertically disposed guide members, a vertically positioned and centrally located screw-threaded guide-way member rigidly secured to the upper surface of the traversing member and adapted to receive a vertical actuating screw member, a vertically positioned screw member adapted to being actuated in the screw-threaded vertical guide-way member, means for rotating the screw member and a rectangular shaped upper member adapted to move with the previously mentioned traversing member, said upper member having a V-shaped depression in its upper surface, and a plurality of vertically positioned guide members rigidly secured to the lower surface of the upper member and adapted to move vertically in the perforations in the guide way members rigidly secured to the traversing member and the previously mentioned vertical screw member adapted to vertically actuate the upper member.

In testimony whereof, I have signed this specification in the presence of two subscribing witnesses.

GEORGE W. TROUTMAN.
